DERRICK

Joseph E. Gadbois, Danielson, Conn.

Original application November 28, 1932, Serial
No. 644,706. Divided and this application
February 15, 1933, Serial No. 656,882

7 Claims. (Cl. 212—68)

This invention relates to improvements in hoisting apparatus and is directed more particularly to improvements in apparatus for rotating the mast of hoisting derricks and the like, and this application is a division of an application, Serial No. 644,706, filed by me on November 28, 1932.

The principal objects of this invention are directed to a derrick structure including means for 10 rotating the derrick mast and according to special features of the invention the said means consists in a broad way of actuating mechanism for rotating the mast which is adjustable about the axis of rotation thereof so that an operator may rotate 15 the derrick mast at different locations about the axis of rotation thereof.

Various objects and advantages of the invention will be more fully hereinafter referred to in connection with the accompanying drawing 20 which illustrates the present preferred form of the invention.

In the drawing:

Fig. 1 is a small scale partial elevational view showing a derrick having the novel features of 25 the invention associated therewith.

Fig. 2 is a plan view at a larger scale on the line 2—2 of Fig. 1, and

Fig. 3 is a sectional elevational view on the line 3—3 of Fig. 2.

Referring now to the drawing more in detail the invention will be fully described.

In Fig. 1 there is shown a portion of a derrick mast 2 and of a boom 4 pivoted thereto at 6 for swinging movements. The mast 2 has its lower 35 end seated on a plate 3 or the like so that it may rotate whereby the boom may be positioned in various radial positions relative to the axis of rotation of the mast. It is to rotate the mast on its axis that the features of this invention are directed and such features will now be described.

A supporting structure having inner and outer members 10 and 12 is provided and is supported by brackets 14 secured to the plate 3. These supports are slotted as at 11 and 13. The mast 2 is provided with a toothed member preferably in the form of a gear 16 which is engaged by an actuating means now to be described.

A gear member 15 is engageable with the gear member 16 and is fixed to the inner end of a shaft 20. A projection 22 at the forward end of the gear and which may be an end of shaft 20 is receivable in the slot 11 of the member 10. A sleeve portion 24 passes through the slot 13 of the support 12 and has a collar 26 disposed at the 55 rear side of the gear 15 and the inner side of

the outer support 12. The shaft 20 is rotatable in this sleeve 24.

A washer or collar 28 surrounds the sleeve 24 outside the support 12 and a manually operable clamping member 30 is in threaded engagement 60 with the sleeve 24 which is threaded as shown. Means such as a hand wheel 32 is carried by the outer end of shaft 20 to facilitate rotation thereof.

By turning the member 30 in one direction or the other it is brought into and out of clamping 65 position so that the members 26 and 28 clamp the sleeve to member 12 and thereby hold the actuating mechanism against movement about the axis of rotation of the mast.

With the actuating mechanism clamped to the 70 support the shaft 20 may be rotated by means of the hand wheel 32. As the shaft 20 is rotated the gear on the forward end thereof and in mesh with the gear 16 of the mast causes the mast to be rotated. By moving the mechanism relative to 75 the support members and about the axis of rotation of the mast the operator may assume various positions and at the same time rotate the mast on its axis of rotation.

It will be noted that the inner end of the gear 80 is guided in the inner support 10 so that the shaft 20 is suitably journaled for rotation at all positions. By providing the actuating mechanism so that it is adjustable or so that it may be moved into various positions of adjustment about the mast, it is possible to rotate the mast into various 85 locations for the operation of the boom and in that way the greatest flexibility of operation of the derrick is obtained.

Having described the invention in the form at 90 present preferred what I desire to claim and secure by Letters Patent of the United States is:

1. A derrick comprising in combination, a mast rotatable on a base, a support on the base extending around the axis of the mast and provided with a slot, a bearing structure movably adjustable along said slot, a shaft journaled for rotation in said bearing structure, means to clamp the structure in said slot and driving connections associated with said shaft and mast. 95

2. The combination with a derrick mast rotatable on a base, of means for rotating said mast comprising, a support, including outer and inner support members provided with slots disposed concentrically relative to the axis of the mast, a gear on said mast, a gear between said slotted members in engagement therewith, a sleeve for clamping opposite sides of said outer member and an actuating shaft extending from said gear through said sleeve all adapted and arranged whereby the 100
105
110

clamping members may be moved about the axis of said mast to facilitate rotation of the actuating shaft in various positions about the axis of rotation of the mast.

5 3. The combination with a derrick mast rotatable on a base, of means for rotating said mast comprising, a support including outer and inner support members provided with slots disposed concentrically relative to the axis of the mast, a 10 gear on said mast, a gear between said slotted members in engagement therewith, a sleeve for clamping opposite sides of said outer member and an actuating shaft extending from said gear through said sleeve all adapted and arranged 15 whereby the clamping members may be moved about the axis of said mast to facilitate rotation of the actuating shaft in various positions about the axis of rotation of the mast, the said outer and inner members being disposed in substantially 20 vertical planes with the slots extending transversely thereto whereby the axis of the actuating shaft is disposed on a substantially horizontal plane.

4. The combination with a derrick mast rotatable on a base, of means for rotating said mast comprising, a support including outer and inner spaced members disposed concentrically of the axis of said mast and in vertical planes which are slotted transversely, a driven gear on said mast, a 25 sleeve movable along a slot of one of said members, clamping means associated with said sleeve for clamping the same to said member, a shaft rotatable in said sleeve, a drive gear on said shaft in mesh with the driven gear and a projection at the forward side of said drive gear movable in the slot of the other member.

5. The combination with a derrick mast rotatable on a base, of means for rotating said mast comprising, a support including outer and inner spaced members disposed concentrically of the 30 axis of said mast and in vertical planes which are

slotted transversely, a driven gear on said mast, a sleeve movable along a slot of one of said members, clamping means associated with said sleeve for clamping the same to said member, a shaft rotatable in said sleeve, a drive gear on said shaft in mesh with the driven gear and a projection at the forward side of said drive gear movable in the slot of the other member, the said clamping means including collars associated with said sleeve on opposite sides of the member and a member threaded on said sleeve for urging said collars into clamping relation with said member. 80

6. The combination with a derrick mast rotatable on a base, of means for rotating said mast comprising, a support including outer and inner spaced members disposed concentrically of the axis of said mast and in vertical planes which are slotted transversely, a driven gear on said mast, a sleeve movable along a slot of one of said members, clamping means associated with said sleeve for clamping the same to said member, a shaft rotatable in said sleeve, a gear thereon in mesh with the driving gear and a projection at the forward side of said gear movable in the slot of the other member, the said clamping means including a collar on said sleeve between said last-named gear and one side of said member, a collar movable on said sleeve at an opposite side of said member and a member threaded on said sleeve for urging said collars against said member. 85 90 95

7. A derrick comprising in combination, a mast rotatable on a base, a support on said base extending the axis of the mast having spaced inner and outer members, a bearing structure movably adjustable on said members, a shaft journaled 100 for rotation in said bearing structure, and means for clamp the bearing structure to one of said members, and driving connections associated with said shaft and mast. 105 110
